UNITED STATES PATENT OFFICE.

WILLIAM C. STARKEY, OF MANSFIELD, OHIO, ASSIGNOR TO THE OHIO BRASS COMPANY, OF MANSFIELD, OHIO, A CORPORATION OF NEW JERSEY.

WINDING DEVICE.

1,372,046.

Specification of Letters Patent. Patented Mar. 22, 1921.

Application filed September 13, 1919. Serial No. 323,641.

To all whom it may concern:

Be it known that I, WILLIAM C. STARKEY, a citizen of the United States of America, residing at Mansfield, in the county of Rich-
5 land and State of Ohio, have invented cer-
tain new and useful Improvements in Wind-
ing Devices, of which the following is a
specification.

My invention relates to improvements in
10 winding devices and similar devices for ap-
plication to spring motors, trolley retrievers,
etc. The device is particularly applicable to
trolley retrievers which are adapted to pull
the trolley pole down below the overhead
15 construction whenever the collector or trol-
ley wheel leaves the trolley wire. Devices
of this character usually comprise a spring
actuated drum on which the trolley rope is
wound and which normally operates to keep
20 the trolley rope taut as the pole moves up
and down when traveling along the trolley
wire, a powerful retrieving spring normally
held under tension and out of connection
with the drum, and mechanism for auto-
25 matically releasing and interlocking the re-
trieving spring with the drum when the trol-
ley pole leaves the wire so that the drum
will be rotated in a direction to wind up the
rope thereby to pull down the pole. After
30 the device has operated to pull down the
trolley pole it becomes necessary to rewind
the retrieving spring and restore the parts
to normal operating positions. This is usu-
ally accomplished by the operator pulling
35 outward upon the trolley rope; that is un-
wind it from the drum whereby the drum
will be rotated in the direction to wind up
the spring and reset the device. In practice
this resetting operation is a very difficult
40 task for the operator to perform from his
station in the car as the operator is com-
pelled to pull out or unwind the rope against
direct action of the retrieving spring which
of necessity must be wound up to a very
45 high tension in order to overcome action of
the trolley base springs when the device op-
erates to pull down the trolley pole.

My invention seeks to obviate the neces-
sity of the operator pulling out or unwind-
50 ing the trolley rope against direct action of
the retrieving spring to restore the device to
normal operating condition and has for its
primary object the provision of improved
means whereby the device may be easily and

conveniently reset by simply rotating a 55
crank or handle.

Another object of the invention is to pro-
vide in a device of the character referred
to improved resetting means controlled by
shifting the handle from one position to an- 60
other.

A further object is to provide means for
yieldably maintaining the handle in inop-
erative position.

A still further object of this invention is 65
to provide an improved device of this char-
acter which will be simple, durable, reliable
and compact in construction, and effective
and efficient in operation.

To the attainment of these ends and the 70
accomplishment of other new and useful ob-
jects, as will appear, the invention consists
in the features of novelty in the construc-
tion, combination and arrangement of the
several parts to be hereinafter more fully 75
described and claimed and shown in the ac-
companying drawing illustrating one em-
bodiment of the invention, and in which:—

Figure 1 is a view in perspective of an
ordinary trolley retriever shown as equipped 80
with my improved rewinding or resetting
means, and in which the handle is shown in
inoperative position in solid lines, and in op-
erative position in dotted lines.

Fig. 2 is a detail view of the rewinding 85
mechanism showing the parts in operative
position.

Fig. 3 is a side elevational view of the de-
vice shown partly in section to illustrate
more clearly the constructional arrangement 90
of the various parts and showing also my
improved resetting means in inoperative po-
sition.

Fig. 4 is a view looking at the inside of 95
the cover showing the rewinding gears.

Fig. 5 is a sectional view substantially on
the line 5—5 of Fig. 3, and showing the 100
retriever disk in interlocked relation with
the case and the drum free to rotate in either
direction.

Fig. 6 is a similar view showing the mech-
anism in the act of unlocking the disk and
also showing the retriever disk unlocked 105
from the case and about to commence its re-
trieving action.

The same reference characters indicate the
same parts throughout the several views.

Referring to the drawings and which

illustrate the embodiment of the preferred form of my invention shown as applied to a trolley retriever comprising a casing 1 having a cover 2 removably secured thereto in the usual manner, the casing is formed with a recess 3 wherein is mounted a power or retrieving spring 4 having its outer end secured to the casing, as by rivets 5, and its inner end connected to the hub 6 of a retriever disk 7 in any suitable or well known manner. The disk 7 is rotatably mounted upon a shaft 8 secured in the casing and is adapted to rotate in one direction by action of the spring 4 and when rotated in the opposite direction winds up the spring. The disk is formed with a peripheral flange 9 provided with a suitable slot wherein is arranged a double latch adapted to normally lock the disk to the casing against relative rotation and to hold the retrieving spring under tension. This latch comprises two levers 11 and 12 pivoted at 13 and 14 respectively to the disk and having their inner or adjacent ends pivotally connected together so that they will both move simultaneously and forming substantially a knuckle jointed device, as shown more clearly in Figs. 5 and 6. When the latch is in locking position its free ends 15 and 16 project outward beyond the periphery of the disk and in position to engage lugs 17 and 18 formed in the casing, see Fig. 5, and in which position the disk will be interlocked with the casing against relative rotation in either direction and the retrieving spring held under tension.

Rotatably mounted, preferably upon another hub extension 19 of the disk is a drum 20 adapted to receive the trolley rope 21, and which is formed with a compartment 22 wherein is mounted a service spring 23 which is wound and adapted to rotate the drum in a direction to keep the trolley rope taut so as to render the device instantly responsive to the abnormal fluctuations of the trolley pole. The drum normally follows the movement of the trolley pole and in case of an abnormal rise in said pole is arranged to actuate mechanism which will unlock the retriever disk and connect it with the drum so that the latter will be rotated in a direction to wind up the rope and pull down the pole. In order to throw in the latch to release the retriever disk the drum carries a plurality of centrifugal dogs 24 which are pivotally mounted in suitable sockets or bearings 25 formed in bosses 26 on the side of the drum adjacent the retriever disk. Under normal operation these dogs are yieldably maintained in inward or retracted position by springs 27, the free ends of the dogs resting against the adjacent bosses, as shown in Fig. 5. The dogs are arranged so that they will be sensitive to abnormal fluctuations of the trolley pole, such for instance as when the pole leaves the wire and flies

upwardly. Because of the undue speed of the drum incident to the quick upward movement of the pole the dogs will move outwardly and against the peripheral flange 9 on the disk under the action of centrifugal force.

By referring to Fig. 5 it will be noticed that when the latch is in locking position its knuckle lies within the flange 9 of the disk and hence within the path of the free ends of the dogs 24 when thrown outwardly. In consequence, the tripping dog which at the instant is nearest to the joint of the latch, will strike said joint and force it outwardly, thus throwing the ends 15 and 16 of the latch inwardly and thereby release the retriever disk which will then be free to rotate by action of the retrieving spring.

Assuming now that the latch has been thrown out and the retriever disk released, as indicated in Fig. 6, it now remains to lock the disk and drum together. This is accomplished by the tripping dog which, after actuating the latch to release the disk, passes the latch and continues until it reaches the shoulder 28 formed in the flange 9 of the retriever disk. By thus engaging said shoulder the tripping dog positively interlocks the retriever disk and drum and the latter will be carried with the disk and will wind up the trolley rope.

The retriever mechanism so far described is a part of that shown and described in Gierding Patent No. 1,212,343, dated Jan. 16, 1917, and includes such parts only as are necessary to obtain a clear understanding of the present invention. A complete description of the mechanism and operation of the retriever may be had by referring to the above patent. While I have shown my invention applied to this particular type of trolley retriever, it will be understood that it is not limited thereto, as I contemplate applying the invention to any trolley retriever, reeling device, or the like wherein a powerful spring is employed which must be wound up or reset.

After the retriever has operated to wind up the trolley rope and pull down the pole it becomes necessary to restore the parts of the device to their normal operating condition, that is, the retriever spring must be wound up or reset. For this purpose and in accordance with my invention, I provide a gear 30 rotatably mounted upon a bearing 31 projecting from the inner surface of the cover 2. This gear rotates with the drum and is interlocked therewith by means of one or more pins 32 secured to the gear and extending within suitable apertures provided in the drum, as shown.

The cover 2 is formed with a chamber or housing 33 comprising a bearing 34 wherein is slidably and rotatably mounted a stem 35 having a driver or pinion 36 secured to

its inner end. A spring 37' is compressed between the pinion 36 and the end wall of the housing and constantly urges the pinion to move in the direction toward the gear 30.

5 Pivots secured to the outer end of the stem 35 is a crank 37 by means of a pin 38 which is offset or located at such a point on the crank, so that by swinging or rotating the crank about its pivot point the stem may be moved axially to carry the pinion 36 into or out of operative engagement with the gear 30. A spring holder 39 is provided and may be secured to the cover by any suitable means, such as rivets 40, for yieldably maintaining the crank in normal inoperative position as shown in Fig. 3. In this position of the crank the driver 36 is held out of engagement with the gear 30, or in inoperative position by means of the surface 41 of the 20 crank coacting with the end surface of the housing 33, and the gear 30 is free to rotate with the drum. For resetting or rewinding the retriever the crank is moved to the position shown in Fig. 2, and in which position the driver 36 is in engagement with the gear 30. Then by turning the crank in one direction, rotary movement may be imparted to the drum in a rope unwinding direction through the connected gears. This 25 rotation of the drum operates to wind up the power spring through the connecting mechanism.

From the foregoing it will be obvious that the retriever may be easily and conveniently reset by simply turning the crank, instead of pulling out on the trolley rope, and that by varying the size of one or both of the gears the parts may be designed to require any predetermined amount of pressure on the crank to rewind the power spring. It will also be noted that the end of the crank 37 pivotally connected to the stem 35 forms substantially a cam device, and will hereinafter be referred to as such.

45 Having thus fully described my invention and illustrated one embodiment of the same, I do not wish to be limited to the details of the construction shown since these can be obviously changed without departing from the spirit and scope of this invention.

I claim:—

1. A spring motor provided with a gear to rotate with same, having in combination therewith a winding device comprising a pinion adapted to move into and out of engagement with the gear but normally held out of engagement with the gear, a handle to rotate the gear and movable into and out of operating position in a plane parallel to the axis of the motor and arranged to automatically disengage the pinion from the gear when the handle is moved out of the operating position and means to automatically engage the pinion with the gear when

the handle is moved into the operating position whereby the spring motor may be wound by rotating the handle about its axis.

2. A spring motor provided with a gear to rotate with same, having in combination therewith a winding device comprising a pinion adapted to move into and out of engagement with the gear but normally held out of engagement with the gear, a handle to rotate the gear and movable into and out of operating position and arranged to automatically disengage the pinion from the gear when the handle is moved out of the operating position and means to automatically engage the pinion with the gear when the handle is moved into the operating position whereby the spring motor may be wound by rotating the handle about its axis.

3. A spring motor provided with a gear to rotate with same, having in combination therewith a winding device comprising a pinion adapted to move into and out of engagement with the gear but normally held out of engagement with the gear, a handle to rotate the gear and movable into and out of operating position and arranged to automatically disengage the pinion from the gear when the handle is moved out of the operating position and permit moving the pinion into engagement with the gear when the handle is moved into the operating position whereby the spring motor may be wound by rotating the handle about its axis.

4. A spring motor provided with a gear to rotate with same, having in combination therewith a winding device comprising a pinion adapted to move into and out of engagement with the gear but normally held out of engagement with the gear, a handle to rotate the gear and movable into and out of operating position and arranged to disengage the pinion from the gear when the handle is moved out of operating position and means to automatically engage the pinion with the gear when the handle is moved into the operating position whereby the spring motor may be wound by rotating the handle about its axis.

5. A spring motor mounted to a support and having in combination therewith a gear arranged to rotate therewith, a stem secured to the support and arranged to move axially thereof, a pinion secured to the stem to engage and disengage the pinion when moved axially with the stem, a handle movably secured to the stem to rotate the stem and pinion and having two positions, an operating and an inoperating position, and means to move the stem and pinion in one direction axially when the handle is moved to the inoperating position and hold it in said position and means to move the stem and pinion in the other direction axially when the handle is moved to the operating position to engage the pinion with the gear.

6. A reeling device comprising a drum, a casing, a spring motor in the casing and connected to the drum, a handle adapted to move into and out of operating position, a gearing between the handle and the motor to wind the motor, means for automatically moving the gearing into operating relation with the motor, and means for automatically moving the gearing out of operating relation with the motor when the handle is moved out of operating position.

7. A winding device for a mechanism comprising a frame, a gear secured to the mechanism to be wound and to rotate therewith, a pinion movable into and out of engagement with the gear, a stem mounted on the frame and secured to the pinion, a handle movably connected to the stem for rotating the stem and pinion and having two positions, an operating and an inoperating position, and means on the handle coacting with means on the frame for automatically moving the pinion out of engagement with the gear when the handle is moved to an inoperating position.

8. A winding device for a mechanism comprising a frame, a gear secured to the mechanism to be wound and to rotate therewith, a pinion movable into and out of engagement with the gear, a stem mounted on the frame and secured to the pinion, a handle movably connected to the stem for rotating the stem and pinion and having two positions, an operating and an inoperating position, and means for automatically moving the pinion into engagement with the gear when the pinion is moved to an operating position.

9. A winding device for a mechanism comprising a frame, gearing adapted to engage

the mechanism to wind the same, a handle for actuating the gearing, means for automatically throwing the gearing into and out of operating position, said means operating by throwing the handle into or out of operating position and means for holding the handle in an inoperating position when not in use.

10. A winding device for a mechanism comprising a support to which the mechanism is secured, a gear arranged to rotate with the mechanism, a stem mounted on the support and having its axis displaced with respect to the axis of the gear and arranged to move axially of the support, a pinion secured to the stem to engage and disengage the pinion when moved axially with the stem, a handle movably secured to the stem to rotate the stem and pinion and having two positions, an operating and an inoperating position, and means to move the stem and pinion in one direction axially when the handle is moved to the inoperating position and hold it in said position and means to move the stem and pinion in the other direction axially when the handle is moved to the operating position to engage the pinion with the gear.

11. A winding device for a mechanism comprising a frame, gearing adapted to engage the mechanism to wind the same, a handle for actuating the gearing, means for automatically throwing the gearing into and out of operating position, said means operating by throwing the handle into or out of operating position.

In testimony whereof I affix my signature.

WILLIAM C. STARKEY.
